UNITED STATES PATENT OFFICE.

THOMAS P. ENRIGHT, OF STERLING, ILLINOIS, ASSIGNOR OF ONE-HALF TO JOHN H. LAWRENCE AND ONE-HALF TO EDWIN F. LAWRENCE, OF STERLING, ILLINOIS.

FRICITION HINGE.

Application filed July 1, 1925. Serial No. 40,753.

My invention relates to leaf hinges, and has for its object to provide a hinge of that type with means by which the freedom of movement of the leaves with respect to each other may be nicely regulated. For some uses,—for example in hanging French windows, it is desirable that the hinges used be so constructed as to interpose frictional resistance to the swinging of the window so that they will not turn too easily, as where such windows swing freely, it is necessary to provide hooks or some other form of device to secure the window in a more or less open position and prevent it from slamming. A hinge that will present considerable frictional resistance to the swinging of such windows has long been recognized as desirable, and particularly one that could be conveniently adjusted to regulate such frictional resistance, but so far as I am aware, prior to my present invention no such hinge has heretofore been devised. The hinge which forms the subject matter of this application does, however, meet these conditions very satisfactorily, as will be apparent from the following description thereof in connection with the accompanying drawings. The features that I regard as new and claim as my invention are set forth in the appended claims.

In the accompanying drawings,—

Fig. 1 is a perspective view illustrating my improved hinge applied to a French window, part only of which is shown;

Fig. 2 is a somewhat similar view showing the hinge in vertical section;

Fig. 3 is a partial elevation showing the lower portion of the hinge;

Fig. 4 is a perspective view of one of the bushings that form a part of the hinge;

Fig. 5 is a fragmentary view showing the lower end of the lower knuckle of the hinge; and

Fig. 6 is a perspective view of the lower cap or button that cooperates with the knuckle shown in Fig. 5.

Referring to the drawings,—7 indicates part of a window frame and 8 part of a French window hinged thereto by means of my improved hinge which comprises two leaves 9 and 10, one of which is secured to the window frame and the other to the window in the usual way. In the arrangement shown the leaf 9 is provided with upper and lower knuckles 11, 12, respec-

tively, spaced apart to receive between them the knuckle 13 of the leaf 10. As clearly shown in Fig. 2, the width of the leaf 10 is somewhat less than the distance between the knuckles 11, 12, the purpose of which arrangement will presently be explained.

Fitted in the bore of the knuckle 11 is a bushing 14, preferably of brass, which bushing is slightly longer than the width of the knuckle 11 and is provided at its lower end with an annular flange 15 that bears against the lower end of said knuckle. The arrangement is such that when the bushing is in place its upper end projects slightly above the upper end of said knuckle, as clearly shown in said figure. The bushing 14 has a driving fit in the knuckle 11, or is otherwise arranged so that it rotates with said knuckle but may move endwise therein.

In like manner the lower knuckle 12 is provided with a bushing 16 similar in all respects to the bushing 14, except that it is reversely arranged, its annular flange 17 abutting against the upper end of the knuckle 12, while the lower end of said bushing projects slightly below the lower end of said knuckle.

The knuckle 13 of the leaf 10 is provided with two bushings 18, 19 fitted in its upper and lower ends, respectively, in the same manner as the bushings 14, 16 are fitted in the knuckles 11, 12. The bushing 18 is provided at its upper end with an annular flange 20 that abuts against the upper end of the knuckle 13 and also bears against the proximate end of the bushing 14 and the annular flange 15 thereof. Similarly the bushing 19 is provided at its lower end with an annular flange 21 that in like manner cooperates with the bushing 16 and flange 17. To this end the length of the knuckle 13 is such that when its bushings are in place it will fit closely between the bushings carried by the upper and lower knuckles 11, 12, which of course requires that the knuckle 13 be made somewhat shorter than the distance between the knuckles 11, 12.

The hinge is provided with a pintle 22 that passes through the several bushings and is provided at one end, preferably its upper end, with a head 23 that overlies the upper end of the bushing 14 and is provided with a groove 24 adapted to receive a screw driver. The lower end of the pintle 22 is screw-threaded, as shown at 25 in Fig. 2,

and is adapted to receive a cap or nut 26 which screws on the screw-threaded part 25 of the pintle.

As best shown in Fig. 6, the inner face 5 of the cap 26 is provided with one or more lugs 27 that are adapted to engage notches 28 in the lower end of the knuckle 12, as best shown in Figs. 3, 5 and 6, when the cap is screwed up on the pintle, or rather 10 when the pintle is screwed into the cap.

From the foregoing description it will be understood that by screwing the pintle 23 into the cap 26, which may be easily accomplished by the use of a screw driver, since 15 the cap is held against rotation by the engagement of the lugs 27 with the notches 28, pressure will be brought to bear against the ends of the bushings 14, 16, tending to move them through the knuckles in which 20 they are mounted and force them together to bind them tightly against the bushings 18, 19 carried by the knuckle 13. Inasmuch as the several bushings rotate with the several knuckles in which they are mounted, it will 25 therefore be apparent that the frictional engagement between the upper and lower pairs of bushings will resist swinging of the leaves of the hinge with relation to each other, and that the extent of such resistance may be 30 nicely controlled or regulated by turning the pintle in one direction or the other relatively to the cap 26, which, as has been explained, may be easily accomplished by the aid of a screw driver.

35 While my improved hinge is intended primarily for use on French windows, it may be used for any other purpose to which it is adapted, and the claims hereinafter made are intended to include any other such uses. 40 Furthermore, while I have illustrated my invention as embodied in a three knuckle hinge, and have shown two pairs of bushings, I wish it to be understood that my invention is not restricted to the arrangement 45 shown, but includes such modifications thereof, or variations therefrom, as would occur to those familiar with the art. For example, instead of securing the cap 26 against rotation and rotating the pintle to 50 vary the frictional engagement of the pairs of bushings, the pintle may be held against rotation and the cap rotated for making such adjustment, this being merely a reversal of the arrangement illustrated.

55 What I claim as my invention and desire to secure by Letters Patent, is—

1. The combination with a leaf hinge, of bushings fitted in knuckles of the respective leaves and having annular flanges in frictional engagement with each other, said bushings being arranged to rotate with their respective leaves and one of said bushings being movable toward the other independently of the knuckle in which it is fitted, and means adjustable to vary the frictional

engagement of said bushings with each other.

2. The combination with a leaf hinge, of bushings fitted in knuckles of the respective leaves and having annular flanges in frictional engagement with each other, said 70 bushings being arranged to rotate with their respective leaves and one of said bushings being movable toward the other independently of the knuckle in which it is fitted, and a pintle extending through said bushings 75 and operable to adjust one of said bushings relatively to the other.

3. The combination with a leaf hinge, of bushings fitted in and rotating with knuckles of the respective leaves, said bushings being 80 in frictional engagement with each other, one of said bushings being movable toward the other independently of the knuckle in which it is fitted, and a pintle extending through said bushings and bearing against 85 the outer end of one of said bushings and operable to adjust the frictional engagement between said bushings.

4. The combination with a leaf hinge, of bushings fitted in and rotating with knuckles 90 of the respective leaves, said bushings being in frictional engagement with each other, one of said bushings being movable toward the other independently of the knuckle in which it is fitted, a pintle rotatable extending 95 through said bushings and bearing against the outer end of one of said bushings, a cap screwed on one end of said pintle, and means for holding said cap against rotation with the pintle.

5. The combination with a leaf hinge, of bushings fitted in and rotating with the knuckles thereof, the bushings in the end knuckles being arranged to project beyond the outer ends thereof and being movable toward each other independently of the knuckles in which they are respectively fitted, the bushings carried by the knuckles of the opposite leaves being arranged to have frictional contact with each other, a pintle extending through said bushings, and a cap screwed upon said pintle and cooperating therewith to vary the frictional engagement between said bushings.

6. A leaf hinge comprising leaves having knuckles, cylindrical bushings fitted in the end knuckles and frictionally coacting with the adjoining knuckles to resist relative movement of said leaves, and means for adjusting one of said bushings relatively to the other independently of the knuckle in which it is fitted to vary the frictional resistance tending to impede swinging of the leaves.

7. A leaf hinge comprising leaves having knuckles, bushings fitted in and rotating with said knuckles, the bushing fitted in one of the end knuckles extending outward beyond the same, adjacent ends of said bushings being arranged to have frictional en-

gagement with each other to resist relative movement of the leaves of the hinge, and a pintle extending through said bushings and operable to adjust the frictional engagement between them.

8. A leaf hinge comprising leaves having knuckles, the end knuckles being provided with friction bushings mounted therein and rotatable therewith, said bushings being

movable relatively to each other longitudinally of the axis of the hinge, independently of the knuckle in which they are mounted, to vary the frictional resistance tending to impede swinging of said leaves, and means operable to apply endwise pressure to said bushings to draw them relatively toward each other.

THOMAS P. ENRIGHT.
